PNEUMATIC DEVICE

Charles G. Playfair, Los Angeles, Calif.

Application April 19, 1937, Serial No. 137,888

6 Claims.

(C.I. 309—2)

The present invention relates to a pneumatic conduit construction broadly adapted to provide air passages in various equipments.

Although not specifically limited thereto the present invention will be particularly described in application to a barrel device for a pneumatic tool which may be utilized for the actuation of polisher heads, cutting devices, saws, and other reciprocating mechanisms or implements.

In the usual type of pneumatic tool with a barrel and piston, it is necessary to provide a valve means for alternately changing the pressure on opposite sides of the piston or differential pressure responsive device, which valve is connected with opposite ends of the piston by external tubing or passageways which must be most carefully and laboriously drilled into the cylinder body.

Even where the cylinder is of relatively heavy metal of substantial thickness increasing the weight of the tool, it is most difficult to drill a straight passage therethrough for a considerable length to assure communication between the opposite sides of piston and the valve construction. And in spite of the high cost of these drilled passages it has been found preferable to utilize them as compared to the difficulties encountered with external piping which prevents satisfactory gripping of the barrel and which is subject to being bent, damaged or broken upon handling.

It is therefore among the objects of the present invention to provide an improved pneumatic tool construction which may be readily and inexpensively manufactured at low cost, and which will provide passageway connections between the valve and the opposite sides of the piston, all with necessity of utilizing external piping and long drilled passageways thereon.

Another object is to provide a pneumatic construction generally adaptable for pneumatic devices or for other purposes where air, gases or fluids are to be by-passed or controlled in their flow by means of valving means in connection with a main container, cylinder or passageway, without the necessity of utilizing an external piping and without the need for providing long drilled passageways.

In designing pneumatic tools of the character above described and particularly provided with elongated barrels, it has not been found most satisfactory to provide reversing valve constructions or other valve mechanisms which must be actuated by external connections from the movement of the piston.

Particularly where a rotary valve is employed

to reverse connections to the piston and alternate the differential pressure applied thereto, it has not been found most satisfactory to use pinion and rack constructions where the rack is actuated by a lost motion connection with the piston or with the reciprocatory element whether it be a reciprocating polishing or friction head, cutting tool, a file or some other implement.

It is therefore among the further objects of the present invention to provide a valve construction for a pneumatic tool of the character described, which valve construction may be actuated by the piston directly without the necessity for external rack and pinion connections and without substantial increase in the bulk or expense of the pneumatic tool.

A still further object of the present invention is to provide an improved polishing head for a pneumatic tool of the character described which will readily accommodate itself to surfaces of various curvatures and shapes.

Other objects will be obvious or will appear during the course of the following specification.

In accomplishing the above objects it has been found most satisfactory to provide a cylinder say of steel or bronze tubing, which tubing is preferably punctured or holed in desired places where ports for pneumatic ingress or egress are desired.

These ports then may be covered by inverted trough or channel members designed to connect the desired ports, and these trough or channel members preferably are of sheet metal and flanged and the ports and trough or channel members are so arranged that the members will extend longitudinally on the outside of the steel or other barrel, parallel to the axis.

These flanges may then be line-welded or spot-welded or even soldered to the body of the liner.

The tube thus prepared with the flanged channel or trough members attached thereto is then positioned in a proper mold or die, into which a low melting or metal alloy, preferably aluminum, is poured, which metal alloy will then enclose the liner and the trough members attached thereto effectively sealing the various channels and troughs from each other and giving a relatively light weight cylinder construction which may be utilized as the handle of the tool with its initial roughened casting left as is, without finishing since this provides a better hand grip.

Within the barrel is preferably positioned a reciprocating valve and a piston, the valve being at one end and the whole tool being controlled by a manually actuated valve to admit or cut off air pressure thereto.

The reciprocating valve is preferably actuated by the air pressure and by the piston in its motion to move backwardly and forwardly, assuring the desired reciprocating motion of the piston.

The polisher head which is shown by way of illustration preferably is supported on a rod, extending forwardly from said piston, and carried in an external tubular element substantially forming an extension of said cylinder, said tubular element may be provided with a handle at its external end and the tubular element may be slotted to receive a bracket for carrying the polishing head, cutting tool or other device.

The polishing head is preferably so connected with said bracket as to permit movement in two directions and give a universal joint effect.

Other features will be specifically described in connection with the drawings, which show by way of illustration and not by way of limitation, one of the many possible embodiments of the present invention.

In the drawings:

Fig. 1 is a longitudinal section view of one form of pneumatic device according to the present invention.

Fig. 2 is a sectional view of the barrel and valve upon the line 2—2 of Fig. 1 with the valve in a different position.

Fig. 3 is a transverse sectional view at right angles of Fig. 1 with the barrel and valve in section and with the piston and valve in a different position than shown in Fig. 1.

Fig. 4 is an enlarged transverse sectional view upon the line 4—4 of Fig. 2, showing the barrel and valve construction.

Fig. 5 is an enlarged transverse sectional view of the barrel with the piston and valve removed therefrom.

Fig. 6 is a perspective view and partial section with the cast metal casing or covering broken away to more clearly show the construction.

Figs. 7 and 8 are enlarged diagrammatic sectional views illustrating the valve and piston operation.

Fig. 9 is a sectional view illustrating the end packing of the cylinder construction.

Referring to Figs. 1 to 3 the barrel A, provided with a piston B, an automatic valve C, a hand valve D, and an implement E taking the form of a polishing head.

The barrel to which the present invention is particularly directed is best shown in Figs. 4 to 6 and it consists of a steel or metal liner 20, which is punctured or holed at suitable places indicated at 21 and 22 in Fig. 5.

The ports 21 and 22 are preferably so arranged longitudinally at the barrel that cooperating ports may be covered by the trough members 23, 24, 25, 26, 27, 28, said trough members preferably being spot-welded at their flanges 29 to the body of the liner or sleeve 20.

When these trough or channel members 23 to 29 are attached by welding of the flanges 29 to the shell or liner 20, the entire device may be placed into a form or die, in which the aluminum body or cover 30 may be cast thereon to form the structure as best shown in Figs. 4 and 5.

This aluminum body may be left roughened with the irregularities of the die or mold and it may be threaded at its ends, as indicated at 31 and 32, to receive the caps 33 and 34 of the pneumatic device.

The cylinder thus formed is of light weight, may be conveniently gripped, is inexpensively manufactured, and eliminates the need of drill-

ing a cast metal barrel and the use of external piping.

This cylinder construction is the principal feature of the present invention and it is obvious that it may be applied to other devices, not specifically shown and/or described in the drawings of the present application.

The various passageways 23 to 28 may be made of any desired cross sectional area without the regard to sizing of drills or thickness of metal and the casting 30 will assure that no leakage will take place between the various trough and channel members. It is obvious that the construction described and the method of forming pneumatic passages may be applied to other devices such as carburetors or other domed cylindrical structures in which a sheet metal base is employed, suitably ported, the ports of which will be connected by suitable trough or channel members 23 to 28, as shown in Fig. 6.

The thickness of casting of the aluminum sheet 30 may be varied and other metals may be readily employed, if their weights and melting points favorably compare to that of aluminum.

The valve structures C and D are not shown in detail in Figs. 1 to 3, the valve structure C being shown best in Figs. 7 and 8.

In the arrangement shown in Fig. 1, the air enters through the hose or tube 35, as indicated by the arrow 36 (see Figs. 1 and 3), and then passes the hand valve D, which is contained in the head of the cap 33.

As shown the end of the pipe 35 is screwed into a tapped bore 37 in the nipple 38 and enters 35 into the bore 39, which communicates with the peripheral bore 40 in the plunger portion 41 of the push valve 42. The push valve 42 is held in position by threaded nut 43 and the spring 44 tends to elevate said plunger from the position shown in Fig. 1 to cut off the peripheral groove 40.

Air under pressure will be admitted to the barrel A, the piston B, and the valve C, when the plunger or hand valve D is depressed to the position, as shown in Fig. 1.

In the position of Fig. 1, the passage 45 is feeding the recess 46, from which air under pressure flows through the channels, as indicated by the arrows in Figs. 1, 2, and 3. In Fig. 1 the air is flowing into the right hand chamber F on one side of the piston. This will cause the piston to move to the left, exhausting the air in the left hand chamber G into the atmosphere through passageways in the barrel A and the valve C.

In the position of Fig. 2 the piston B is returning to the right and the valve C is in the inside position.

In Fig. 3, the piston has returned beyond the position of Fig. 2 and in short time will strike the valve C and return it to the position of Fig. 1.

The operation of the valve is more fully shown in the diagrammatic showings of Figs. 7 and 8, to which reference will now be had.

As previously described the air flows into the recess 46 from the inlet conduit 50, the end of which is enlarged at 51. From the chamber 46, when the piston is moving to the right, as indicated by the arrow 52, the air will pass from the chamber 46 through the port 53, the trough member 54, which will be one of the members 23 to 28 of Figs. 4 to 6, through the port 55, through the annular recess 56, to the radial bore 57, the longitudinal bore 58, the radial bore 59, the peripheral groove 60, the port 61, the trough member 62, the port 63 and to the chamber G, caus-

ing the piston B to move in the direction of said arrow 52.

During the movement of the piston in the direction indicated by the arrow 52, the air from the chamber F will be exhausted through the port 71, the trough member 72, the port 73, the peripheral groove 74, and the atmospheric exhaust port 75 to the atmosphere.

It will be noted that shortly before the piston has moved to the position of Fig. 7 in its leftward movement as shown by the arrow 70 of Fig. 8 it has uncovered the port 64. From the port 64 of the air under pressure flows through the trough 65, the port 66 into the chamber 67, the air moving into the chamber 67 will cause the valve C to move from the position of Fig. 8 to the position of Fig. 7, reversing movement of the piston B.

As shown in Fig. 7 the piston will move in the direction 52 until it strikes the valve C and throws it back to the position of Fig. 8, the extension nipple 68 of the piston B cooperating with the recessed extension 69 on the end of said piston C, as shown best in Figs. 1 to 3.

When the piston B strikes the valve C at the end of its movement in the direction as indicated by the arrow 52, the port position will be changed as indicated in Fig. 8 and the piston will then move to the left in the direction indicated by the arrow 70 of Fig. 8. In Fig. 8 the air under pressure will flow from the chamber 46, the port 53, the trough 54, the port 55, the peripheral groove 56, the radial bore 57, the longitudinal bore 58, the radial bore 76, the port 77, the trough 78 and the port 79 into the chamber F.

At the same time, the air being exhausted will flow from the chamber G through the port 80, the trough 81, the port 82, the peripheral groove 83, the bores 84, 85, 86, the peripheral groove 87, to the atmospheric outlet port 88.

The recess 89 having the shoulder 90 and the back plate 91 will cooperate with the enlargement 92' on the back of the valve to limit the reciprocatory motion of the valve C.

The back plate 91 is provided with a central bore 92, carrying the kicker extension 93, and is provided with a recess 94 receiving the enlarged portion 95.

It is thus apparent that the valve C is automatically operated without external gearing or actuating connections to reverse the flow of air under pressure to the piston B, causing frequent reciprocations thereof.

The piston itself is best shown in Figs. 1 to 3, and consists of a rear element 96 which has a threaded connection to the front cup element 97, the bore 98 of said front cup element receiving the actuating rod 99 which has the enlarged head 100, fitting in the recess 101 between the piston elements 96 and 97. The fit between the bore 98 and the piston 99 is such that the piston may automatically align itself in parallelism with the rod 99 even if the axes of the cylinder and rod 99 are not in alignment.

The packing at the other end of the cylinder, as indicated by the letter H in Figs. 1 to 3, is shown in detail in Fig. 9.

In Fig. 9 the cap 34 receives three annular washers, the washers or gaskets 102 and 103 being of leather and the gasket 104 consisting of a steel disk. This steel disk preferably is closely fitted to the rod 99 and holds the gland packing 105 in position.

The bronze bearing 106 closely fits the rod 99

and also the interior of the tube 107, which tube is threaded at 108 to the nipple extension 109 of the cap 34. The lock nut 110 presses the washer 111 against the end of the nipple 109 prevents movement of the cap relative to the sleeve 107. It is apparent, however, that by tightening the cap 34 the gaskets 102, 103, and 104 are locked and sealed and then by turning the tube 107, the gland packing 105 is forced into the recessed end of the sleeve 106 to prevent a leakage around the piston shaft. The lock nut 110 keeps the entire arrangement in position.

Referring to the tubing 107, the end of this tube is threaded, as indicated at 108, where it receives the tapped sleeve element which is provided with outturned ears 114, carrying the handle 115 by means of the screws 116.

The lower portion of the tube is slotted, as indicated at 117. The end of the piston rod 99 is connected at 118 to the plate 119 which projects through said slot 117. The piston rod 99 is slotted and the plate 119 is inserted thereinto and riveted in place. The plate 119 receives the openings 120, which in turn receive the ends 121 of the coil springs 122, the lower end of said springs 122 being attached at 123 by the screws 124 to the polisher head E.

The lower end of the triangular plate 119 is also connected to the polisher plate through a linkage 125 pivotally mounted at 126 to the plate and at 127 to the upwardly projected lugs 128 from the body 129 of said polisher head.

The polisher head is covered by the flexible felt or absorbent material 130 which is in turn covered by the sanded polishing abrasive sheet 131 preferably held in position around its periphery 132 by the snap ring 133.

In operation by grasping the handle 115 in the hand and the roughened surface of the barrel A in the other hand and then by depressing the button D with the back of the hand, the air pressure may be turned on through the tube 35 to actuate both the piston B and the valve C to cause reciprocation of said piston and of said polishing head which may be applied with the desired amount of pressure to the surface being polished or abraded.

The pivot connections 126 and 127 and the linkage 125 will assure a substantially universal connection of the polisher head and will enable movement of said polisher head in various directions.

It is thus apparent that the applicant has obtained a most useful and inexpensive tool of particularly desirable construction.

Many other changes could be effected in the particular features of construction designed, and in methods of operation set forth, without substantially departing from the invention intended to be defined in the claims, the specific description herein merely serving to illustrate certain elements by which, in one embodiment, the spirit of the invention may be effectuated.

What is claimed is:

1. In a pneumatic tool, a pneumatic chamber provided with a thin sheet metal cylindrical shell, a cover for said shell, a plurality of spaced ports in said shell, and a plurality of flanged thin sheet metal trough members forming passages inside of said cover connecting said ports.
2. In a pneumatic tool, a pneumatic chamber provided with a thin sheet metal cylindrical shell, a cover for said shell, a plurality of spaced ports in said shell, and a plurality of flanged thin sheet metal trough members forming passages inside

of said cover connecting said ports, said cover consisting of an aluminium layer cast onto said shell.

3. In a pneumatic tool, a pneumatic chamber provided with a thin sheet metal cylindrical shell, a cover for said shell, a plurality of spaced ports in said shell, and a plurality of passages inside of said cover connecting said ports, said passages taking the form of elongated thin sheet metal troughs spot welded onto the exterior of said chamber.

4. In a pneumatic tool, a pneumatic chamber provided with a thin sheet metal cylindrical shell, a cover for said shell, a plurality of spaced ports in said shell, and a plurality of passages inside of said cover connecting said ports, said shell being a cylinder, said passages taking the form of elongated thin sheet metal troughs on the ex-

terior of said cylinder and said cover taking the form of an aluminium casting.

5. In a pneumatic tool, a pneumatic cylinder consisting of a steel shell, a plurality of ports in said shell, a plurality of elongated thin sheet metal trough members on the outside of the shell, and a die cast aluminium cover in said shell covering said trough members.

6. In a pneumatic tool, a pneumatic cylinder consisting of a steel shell, a plurality of ports in said shell, a plurality of elongated thin sheet metal trough members on the outside of the shell, and a die cast aluminium cover in said shell covering said trough members, the periphery of said trough members being flanged and said flanged portion being welded to said shell.

CHARLES G. PLAYFAIR.
